UNITED STATES PATENT OFFICE

2,377,264

TRAIN ORDER DELIVERING DEVICE

Anthony J. Pieszak and Edward M. Mulcahy,
Dunkirk, N. Y.

Application March 8, 1943, Serial No. 478,398

1 Claim. (Cl. 258—23)

This invention relates to train order delivery devices, and its general object is to provide a device by which orders and messages can be conveniently transferred from a station platform to a member of the crew on a fast moving train with safety and surety in the delivery.

A further object is to provide a train order delivery device that includes forked means for detachably holding a flexible element, such as a cord in the form of a loop for attachment of an order thereto, and the loop is positioned in a manner to readily permit a member of the crew on the train to conveniently slip his arm therethrough for removal thereof from the fork, thus bringing about a successful transfer of the order without injury to the receiver.

A further object is to provide a device of this character, in which the fork is detachable and means is likewise provided for supporting the fork when detached, in an upright position, in order to facilitate attaching the cord thereto.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a side elevation of the device which forms the subject matter of the present invention and illustrates the same in use, with a message attached to the loop.

Figure 2 is a top plan view thereof.

Figure 3 is a sectional view taken approximately on line 3—3 of Figure 1, looking in the direction of the arrows.

Figure 4 is a sectional view taken approximately on line 4—4 of Figure 2, looking in the direction of the arrows.

Figure 5 is a sectional view taken approximately on line 5—5 of Figure 2.

Figure 6 is a perspective view of a block to be used for supporting the fork when the latter is detached.

Referring to the drawing in detail, it will be noted that we have illustrated one of the devices as being secured to a post A, but two may be used and they may be secured to any suitable supporting means in proximity to the train tracks, as will be apparent, so that the loop previously mentioned will be in convenient reach of

a member of the crew on the train for removing the same from the fork. When two of the devices are used, a message can be attached to each, one message for a member of the crew at the front of the train and the other for a crew member at the rear thereof. In any event, the device includes an attaching bracket 1 that is secured to the post by screws, as shown in Figure 1, and formed on and rising from the horizontal portion 2 of the bracket is a cross sectional square pintle 3 having a bearing collar 4 mounted thereon, the collar being shaped to fit the pintle, so as to be held against rotation. Mounted to turn on the collar is a hub 5 that has formed thereon 10 and extending at right angles therefrom for disposal horizontally, a coupling nipple 6 within which is fixed one end of a tubular member 7, for a purpose which will be later described.

The hub is formed with upper and lower annular flanges 8 and 9 respectively, and the bearing collar is formed with a base element 10 about its lower end, upon which the hub 5 normally rests. A concaved depression 11 is provided in the front of the base element for fittingly receiving a convexed lug 12 that is formed on the lower flange 9, the lug being normally held seated in the depression by coil springs 13 which are vertically disposed upon opposite sides of the hub and have their ends connected to the upper flange and the base element respectively. By that construction, it will be seen that the device is self adjustable and that the fork is normally held in position for use against casual movement, but will yield under lateral pressure, as well as return to normal position when released. A pin 14 transverses the upper end of the bearing collar and extends outwardly therefrom for disposal in the path of the hub, to limit upward movement thereof on the collar.

40 The fork includes a stem 15 having secured thereto intermediate its ends a sleeve 16 of a three-way coupling and formed with the sleeve and extending from opposite sides thereof in diverging relation are branch sleeves 17, each 45 having secured therein and extending therefrom relatively long arms providing outer tines 18 for the fork. The inner end portion of the stem provides a short intermediate or central tine 19, while the outer end portion provides a shank 20. The three-way coupling is shown as being formed from a pair of longitudinal half sections secured together by rivet pins 21, that extend through the outer tines and the stem for fixing the same within the sleeves.

55 Secured to the central tine is a spring clip

22 that is formed from a single strand of wire looped midway its ends to provide spaced arcuate clamping members 23 extending along the length of the central tine, as well as held in bearing engagement therewith by coiled portions 24. The clip is adapted to hold a portion of a continuous flexible element 25 such as a cord, clamped to the central tine and the ends of the outer tines are notched as at 26 for receiving portions of the cord, so that the latter provides a substantially triangular shaped loop to which is attached the order or message B by any suitable means such as a short length of cord 27 the message being attached to the outer portion of the loop, as shown in Figure 1.

The tubular member 1 provides a socket for the shank 20 which is detachably secured therein by latching means including a flat spring arm 28, the arm having one end secured to the tubular member for disposal along the length of the upper face thereof, and the tubular member has a notch 29 in its outer end for receiving a keeper pin 30, secured to the shank. The spring arm is provided with a hole for receiving the pin, as best shown in Figure 4, thus it will be seen that the fork is held secured to the tubular member against casual removal or displacement. The spring arm 28 extends beyond the outer end of the tubular member and is bent at an upward and outward angle therefrom to provide a handle 31.

The fork is held associated with the tubular member so that the tines are arranged one above the other for disposal of the loop provided by the cord in a vertical plane, which of course is the most convenient position for a member of the train crew to remove the cord from the fork, the cord being removed merely by the crew member slipping his arm through the loop, and while the clip 22 holds the cord against casual removal, a slight pull thereon will release the same, thus bringing about a successful trans-

fer of the message with minimum effort on the part of the crew member.

While the cord can be attached to the fork when the latter is in applied position, such can be more readily accomplished when the fork is removed. In order to facilitate the attachment, a block 32 is provided for supporting the fork in a perpendicular or upright position, and for that purpose, the block has a centrally disposed bore 33 therein for receiving the shank 20. A recess 34 is provided in the upper face of the block and opens into the bore for receiving the keeper pin 30, so as to prevent turning of the fork relative to the block, as will be apparent.

15 It is thought from the foregoing description that the advantages and novel features of the invention will be readily apparent.

It is to be understood that changes may be made in the construction and in the combination 20 and arrangement of the several parts, provided that such changes fall within the scope of the appended claim.

We claim:

25 In a train order delivering device of the type having a support and a sleeve-like member on the support, and a forked frame having outer tines holding a message supporting cord and a central tine, a three way hollow coupling member having outer tines carrying the outer tines of the fork 30 and a central part carrying the central tine, the central tine extending through both ends of the central part and one end received in the sleeve-like member, an elongated spring arm carried by the sleeve having an opening therein, a pin 35 carried by the end of the central tine received in the sleeve and the sleeve slotted to receive the pin, said spring mounted to receive the pin in the opening therein to detachably mount the fork in the sleeve.

40 ANTHONY J. PIESZAK.
EDWARD M. MULCAHY.
